(57) **CLAIM**

The ornamental design for a fiber optic apparatus, as shown and described.

DESCRIPTION

FIG. 1 is a front-top-right isometric view of a fiber optic apparatus showing the new design;

FIG. 2 is a rear-bottom-left isometric view of the fiber optic apparatus of FIG. 1;

FIG. 3 is a front view of the fiber optic apparatus of FIG. 1;

FIG. 4 is a rear view of the fiber optic apparatus of FIG. 1;

FIG. 5 is a left side view of the fiber optic apparatus of FIG. 1;

FIG. 6 is a right side view of the fiber optic apparatus of FIG. 1;

FIG. 7 is a top view of the fiber optic apparatus of FIG. 1;

FIG. 8 is a bottom view of the fiber optic apparatus of FIG. 1; and,

FIG. 9 is a front-top-right isometric view of the fiber optic apparatus of FIG. 1 shown in an alternate environmental condition.

The broken dash-dash-dash lines are for the purpose of illustrating environmental structure and form no part of the claimed design.
